UNITED STATES PATENT OFFICE.

JOHN S. BAKER, OF EVANSVILLE, WISCONSIN.

LADDER.

No. 869,047.

Specification of Letters Patent.

Patented Oct. 22, 1907.

Application filed July 6, 1907. Serial No. 382 504.

To all whom it may concern:

Be it known that I, JOHN S. BAKER, a citizen of the United States, residing at Evansville, in the county of Rock and State of Wisconsin, have invented certain 5 new and useful Improvements in Ladders, of which the following is a specification.

This invention relates to ladders for windmill or other towers.

It contemplates a novel construction wherein the 10 corner posts or supporting standards of the tower are utilized to form one side of the ladder, a novel manner of attaching angle side pieces to the girths commonly used in structures of this character and a novel arrangement whereby steps of peculiar construction are attached to one corner angle of the tower and to the side rail forming the opposite vertical part of the ladder.

The object of the invention is to provide a construction which will be exceedingly convenient to climb, ship and erect, which will be reliable, strong, sightly 20 and comparatively cheap to manufacture.

I have not deemed it necessary to show the entire windmill tower, but show one of the corner posts or supporting standards, a girth, and the opposite vertical angle piece with a step attached thereto, and the means 25 for attaching the girth to the inner angle pieces.

In the drawings: Figure 1 is a broken perspective view showing the corner support of a windmill tower, girth, step, and means whereby these parts are connected; Fig. 2 is a horizontal sectional view taken on line 2—2 30 of Fig. 1; Fig. 3 is a section taken on line 3—3 of Fig. 1, the girth being in elevation; Fig. 4 is a sectional view of the girth, inner angle pieces, etc.; Fig. 5 is a cross section of the form of step shown in Figs. 1, and 2; Fig. 6 is a top plan view of a modified form of step, and Fig. 7 35 is a top plan or edge view of the step of the form which I prefer, or the step shown in Figs. 1 and 2.

Referring to the drawings, the numeral 1 designates one of the corner supports of the tower, which may of course, be of any suitable length and constructed in 40 proper sections. The numeral 2 designates a girth, which in the present instance I make in the form of an angle presenting top face 3 and side face 4. These girths may be employed at suitable intervals to give the desired strength to the structure.

45 The corner standards of the tower, or posts, are in the form of angle bars having flanges 5 and 6. At intervals, the girths 2 are attached to the angle 6 of the corner posts or standards by means of bolts 7. The numeral 8 designates the inner side piece of the ladder which is formed 50 of a number of angle pieces 9 presenting flanges 10 and 11. Wherever a girth occurs in the tower, which in practice would be about five feet six inches apart throughout the height of the tower, I secure to them the angle pieces 9 by the means which will now be described.

55 The angle pieces overlap each other for a short distance, and the upper and lower ends of the angle pieces

9 are provided with perforations 12 for the passage of a hook bolt 13 whose inner hooked end 14 embraces the top flange or piece 3 of the girth, which girth at this place forms a step. Abutting against the flange 10 of the angle piece 9 is a tubular washer 15, through which the threaded shank 16 of the hook 13 passes and receives the nut 17, which when tightened, firmly secures the girth and the angle pieces together, as is clearly shown in Figs. 1, 3 and 4.

65 The numeral 18 designates a step formed preferably of sheet metal bent into a U-shape or approximately so, as shown in Fig. 5 of the drawings. This construction in cross section occurs throughout the entire length of the step narrowing however, at the ends where said 70 ends are flattened together as shown at 19 and provided with off-sets 20, shown clearly in Figs. 2 and 7.

75 As shown in Fig. 1, one end of the step is inserted into a slightly elongated aperture 21 in the flange 6 of the corner standard of the tower, while the opposite end of the step is passed through a similar aperture or slot 22 in the flange 10 of one of the angle sections of the inner side piece of the ladder. Wherever the girths appear throughout the height of the tower, they serve as steps, and the manner of attaching the inner angle pieces 8 80 is the same with relation to each girth. In practice, the girths occur after each third step, or about five feet and six inches apart.

85 In Fig. 6 I show in plan view a slightly modified form of step. In this instance, the step is angular in form presenting, between its ends a top flange 23 and a side flange 24. The ends are bent as indicated at 25 which is a position in which they would enter the slots in the corner supports and angles 9, in the same manner as that described in connection with Figs. 1 and 2.

90 I do not desire to limit myself to the use of the corner post or support of the tower, as obviously, the ladder may be constructed at the middle of one of the sides of the tower instead of following the corner as shown in the drawings. In this instance, the angle pieces 9 95 would be duplicated. Nor do I limit myself to the form of the steps shown, as they may consist of pipes with flattened ends provided with off-sets adapted to extend through the slots in the angle pieces, or of solid bars with ends flattened and off-sets.

Claims.

1. A ladder of the character described, comprising side pieces having oppositely disposed slots therein, a series of steps having flat off-set ends entering the slots in the side pieces, and retained therein by said off-set ends.

105 2. A ladder of the character described, comprising side pieces having oppositely disposed slots therein, a series of steps formed of sheet metal, U-shape in cross section for the greater part of their length and having flattened ends forming off-sets that enter the slots in the side pieces.

110 3. In a ladder for windmill or like towers, the combination with the corner post or support of the tower, provided with slots or openings; a rail parallel with the corner post and also provided with slots, a plurality of

steps having flattened and off-set ends adapted to enter the slots in the corner post and the rail parallel therewith, and be retained by said off-sets.

4. In a windmill or like tower, the combination with the corner post thereof having slots or openings therein, a rail parallel to said corner post and also provided with slots, a plurality of steps formed of sheet metal, substantially U-shape in cross section for the greater part of their length and terminating in flattened off-set ends, one end being adapted to enter the slot in the corner post and the other to enter the slot in the rail, parallel to said post.

5. In a windmill or like tower, the combination with the tower girths and one corner post of the tower, having slots therein, a rail parallel with the corner post and formed of sections overlapping at the girths and provided with apertures, a hook bolt passing through the ends of the rail sections and embracing the girth whereby the sections of said rail are held together and to the tower girth, and steps suitably attached to the corner post and to the rail.

6. In a ladder for windmill and like towers, the combination with the horizontal girths thereof, two parallel rails forming the side rails of the ladder and provided with slots or openings, the rails being formed of sections with their ends overlapping and provided with apertures, a hook-bolt passing through the apertures and embracing the girth whereby the rail sections are held together and to the girths, and steps substantially U-shaped in cross section for the greater part of their length and provided with flattened ends having off-sets which enter the slots in the side rails.

In testimony whereof I affix my signature in presence of two witnesses.

JOHN S. BAKER.
